(57) CLAIM

The ornamental design for a drinking glass as shown and described.

DESCRIPTION

1. Drinking glass
2. Drinking glass
3. Drinking glass
4. Drinking glass
- 1.1 : Perspective
- 1.2 : Front
- 2.1 : Perspective
- 2.2 : Front
- 3.1 : Perspective
- 3.2 : Front
- 4.1 : Perspective
- 4.2 : Front

The claim is directed to a symmetrical drinking glass with round plan view.

The broken lines depict portions of the drinking glass that form no part of the claimed design.

1 Claim, 8 Drawing Sheets
